UNITED STATES PATENT OFFICE

PER CHRISTIAN CHRISTENSEN, OF LEICESTER, ENGLAND, ASSIGNOR TO G. STIBBE & CO.
LIMITED, OF LEICESTER, ENGLAND, A BRITISH COMPANY

CIRCULAR KNITTING MACHINE

Application filed October 9, 1929; Serial No. 398,496, and in Great Britain October 19, 1928.

This invention relates to circular knitting machines and concerns those of the kind wherein provision is made for varying the number of loops in the knitted courses during knitting of the tube of fabric so that the 5 diameter of the latter is varied.

Mainly the invention has reference to machines for making seamless hosiery and its principal object is to produce an improved circular machine for making a full-fashioned hose, but it is to be understood that the invention is not limited to such application as it may be embodied in a circular machine for producing other goods or fabric wherein fashioning or diameter variation is 10 a desideratum.

For the purpose of the present description however, and for the sake of convenience, the invention will be considered as applied to a circular knitting machine for making 15 seamless, fashioned, plain stockings and like goods.

To enable the invention to be clearly and readily understood examples thereof will be hereinafter described with reference to the 20 accompanying drawings as applied to a circular seamless plain hose knitting machine for fashioning the leg portion of the knitted article.

In the drawings, 25 Figure 1 is an end elevation of a circular knitting machine furnished with fashioning means according to the invention.

Figure 2 is a front elevation of the machine, and

Figure 3 is a sectional plan taken on line III—III of Figure 2.

Figure 4 is a sectional plan of a needle cylinder constructed in accordance with the invention.

Figure 5 is a diagrammatic view showing a convenient layout of needles in said cylinder.

Figure 6 shows different kinds of needles employed in accordance with the invention.

Figure 7 shows different kinds of jacks employed in association with certain of the needles.

Figure 8 is a sectional detail showing one of the said jacks acting on a fashioning needle.

Figure 9 is a sectional detail showing another of said jacks operating on an ordinary needle having a stepped butt for a purpose hereinafter described.

Figure 10 is a developed view of a jack and needle operating cam system. 55

Figure 11 shows a few of the needles and jacks as they appear prior to starting the fashioning operation.

Figure 12 illustrates the initial stage of the fashioning operation. 60

Figure 13 illustrates the manner in which fashioning needle jacks hereinafter referred to are pre-selected for engagement with a raising cam whereby the fashioning needles are brought into action. 65

Figure 14 shows how the pre-selected jacks are levelled up prior to passing a depressing cam which determines the intervals at which the fashioning needles are rendered operative. 70

Figure 15 shows the depressing cam which is represented as being inactive.

Figure 16 shows the raising cam engaged by pre-selected jacks for bringing the corresponding fashioning needles into action. 75

Figure 17 is a sectional plan of a needle cylinder wherein the needle grooves are equally spaced throughout.

Figure 18 is a diagrammatic view showing a convenient layout of needles in a cylinder wherein the grooves are equally spaced as shown in Figure 17, and 80

Figure 19 shows an alternative layout in a similar cylinder.

According to this invention there is provided a circular knitting machine of the independent needle type for the production of fabric fashioned by the introduction of additional loops wherein for the purpose of knitting the additional loops ordinary needles are interspersed with fashioning needles in the same needle bed, said fashioning needles being brought into operation selectively, and means are furnished whereby the ordinary needles adjacent to the fashioning needles are caused to even up their loops with the loops formed by the other needles of the machine both prior to and during the fashioning operation. 85

90

95

100

The needles are slidable in the needle cylinder and the fashioning needles are normally idle. Since the ordinary needles and the fashioning needles, are arranged in the same 5 needle bed, the fashioning needles, when in action, work side by side with the ordinary needles, and when the number of needles in action is increased, the gauge of the machine and consequently of the fabric at that part of 10 the needle circle where the needles are supplemented will be altered. Therefore to ensure the resultant fabric, although increased in diameter, being uniform as regards loop formation and appearance there 15 is employed in conjunction with the fashioning means, an arrangement to vary the loop formation as will be hereinafter described.

In carrying out the invention in a circular knitting machine, such as a seamless hose machine, where the knitted tube is to be 20 fashioned on one side, e. g. at the calf in a stocking, I provide a needle cylinder having sections of different gauges, i. e. as shown in Figure 4, the coarse gauge section containing ordinary needles and the fine gauge section or sections containing both ordinary and 25 fashioning needles.

In making a fashioned tube on such machine, knitting proceeds on the ordinary 30 needles while the fashioning needles remain idle and empty. When fashioning is to be effected the fashioning needles are brought into action one, two or more at a time and thus form additional loops to increase the 35 size of the tubular fabric.

It is to be understood that I may, instead of employing a needle cylinder having sections of different gauges, use one wherein the needle grooves are equally spaced as shown 40 in Figure 17, in which case the fashioning needles may be distributed either in one section of the cylinder or in different sections.

When the needle cylinder is cut to different gauges, the finer one contains the fashioning needles and is of such gauge compared 45 with that of the other section that, when the ordinary needles in said finer gauge section are working without the fashioning needles, said ordinary needles will be of coarser gauge 50 than the other section. By the term "gauge" herein employed it is to be understood that I mean the pitch or spacing of the needles in the needle circle and not the thickness of the needles themselves. It will also be understood 55 that the needles herein referred to as "ordinary" needles are those which are knitting all the time whereas the "fashioning" needles are introduced when required to supplement the knitting complement.

60 In the example already referred to, where the needle cylinder has sections of different gauges, I preferably so actuate the needles that, during the knitting of the small or non-fashioning portion of the tube, the ordinary 65 needles in the fine gauge section draw smaller

or tighter loops than the ordinary needles in the coarse gauge section. The effect of this is that since, as before mentioned, the ordinary needles in the fine gauge section are of coarser pitch than those in the coarse gauge 70 section, the loop formation and appearance of the knitted tube is made uniform all round. I also preferably arrange that when fashioning needles are brought into action these and the adjacent ordinary needles are 75 caused to make longer or slacker loops than those made by the ordinary needles in the coarse gauge section.

The fabric produced is therefore of uniform gauge throughout. 80

Referring to the drawings, the invention is illustrated as applied to a machine of the well known Banner type forming the subject of the patent to Joshua D. Hemphill No. 933,443, although, as will be readily understood, the invention is not limited to application to machines of this type. In the Banner machine the needle cylinder 1 rotates and the cam carrier 2 remains stationary. In general form the machine includes a rotary 90 needle cylinder 1 arranged on a bed 3 (Figs. 1 and 2) extending horizontally from a frame 4 and as usual in a machine of this type the cylinder rotates during the formation of the leg of a stocking and reciprocates during the 95 formation of the heel and toe.

The machine is also equipped with yarn feeding devices indicated generally at 5 by means of which one or more yarns can be supplied to the needles according to requirements. These yarn feeding devices are controlled from a pattern cylinder 6 on the pattern shaft 7 by intermediate connections substantially the same as those described in the specification of Patent No. 933,443. The machine is furnished with a main driving shaft 8 (Fig. 2) having thereon the usual pulleys 9 and a pinion 10 meshing with a large gear 11 known as the "104" gear, from which is also driven in the usual manner the quadrant 12 through the medium of which the reciprocating motion is imparted to the cylinder during the knitting of the heel and toe. The means for rotating and reciprocating the cylinder 1 and operating the pattern shaft 7 are substantially the same as those described in the specification aforesaid and therefore do not require further description herein. The machine is also provided with the usual narrowing and widening pickers 13, 13a 110 shown in Fig. 2.

The machine is intended to commence knitting the article at the toe and from the ankle to fashion the leg by gradually increasing the diameter of the knitted tube by increasing the number of loops in the back half. 115

Referring to Figures 4 and 5, according to one construction the needle cylinder 1 is formed with a section 14 of coarse pitch needle grooves 1a extending approximately $\frac{3}{4}$ 120

of the way round the cylinder, the remaining $\frac{1}{4}$ being disposed centrally of the heel side and divided into three sections 15, 16 and 17, the sections 15 and 16 being of fine gauge and the section 17 of coarse gauge. In the coarse gauge section 14 ordinary needles 18 and 24 (Figure 6) are used; in the coarse gauge section 17 ordinary needles 24 are used; in the fine gauge or fashioning sections 15 and 16, ordinary needles 19 alternate with fashioning needles 20. A convenient arrangement for the combined sections 15, 16 and 17 which may be termed the fashioning section, is a few ordinary needles in the centre, say about ten, and then alternate fashioning and ordinary needles on each side, as indicated in Figure 5.

Now with a needle cylinder formed and equipped as just described fashioning is brought about by bringing the fashioning needles 20 into action selectively on opposite sides of the centre. For instance, fashioning may be commenced by bringing into action first the two fashioning needles on opposite sides of the central group of ordinary needles, and then, after a desired number of courses have been knitted, the next two fashioning needles can be brought into action and so on until all the fashioning needles are in action and the knitting complement has been thereby increased in number.

I may employ any suitable means for bringing the fashioning needles into action. An appropriate and convenient arrangement 35 comprises a series of jacks operated by cams, and this system is advantageous not only because it enables the fashioning needles to be brought into action selectively but also because it enables the stitch forming action of the associated ordinary needles in the fashioning section to be varied as will be more fully described presently.

For my particular purpose I may use jacks similar to those described in British specification No. 210,046. In the present specific example, a jack 21 is disposed under each fashioning needle and a further jack 22 under the ordinary needle or needles associated with it in the fashioning section. That is to say, a jack is disposed under each of the needles in the sections 15 and 16. These jacks are arranged in pairs, and the jacks 22 are constructed and arranged so that when one is raised, as by a cam, it will engage with 50 and raise the next adjacent pair of jacks to a less height, and the jack 22 in this pair, when raised subsequently, will lift the next pair, and so on. Thus each pair of jacks, when raised, selects the next pair preparatory to raising and so on throughout the series.

By the employment of these jacks in conjunction with suitable cams the fashioning needles can be selectively brought into action, 65 and, to enable the fashioning to be carried

out from the centre, the jacks are made right and left hand, as indicated in Figure 11 so that, at each selection, one or more needles on opposite sides of the centre are brought up for use.

Now for the purpose of evening up the fabric as it is fashioned, the following arrangement is adopted. The jacks 21 under the fashioning needles function to raise their needles from an idle track x to a knitting track y (see Figure 10) so that said needles are put into action to form loops. The jacks 22 under the ordinary needles associated with the fashioning needles, i. e. the needles 19 are formed so that when raised they cause said needles to be actuated to draw longer loops than they were doing previously. The purpose of this is to make the gauge of the fabric coarser at that locality where, consequent upon the additional needles coming into action, the needle pitch has become finer.

In the operation of the machine, during fashioning, in one revolution the selected fashioning needles are raised into action by their jacks, which latter may thereby select the jacks of the adjacent ordinary needles, and in the next revolution the said selected jacks may then rise to cause the said ordinary needles to draw longer loops, the raising of these jacks selecting the jacks of the next adjacent fashioning needles preparatory to these being brought into action after a desired number of courses have been knitted.

It is preferred however to arrange for the control of each associated ordinary needle to take place when the fashioning needle comes into action, instead of during the next revolution as just described. That is to say, when each fashioning needle draws its first loop the adjacent ordinary needle will draw a longer loop. This may be achieved by coupling the jacks of the fashioning needle and adjacent ordinary needle so that they operate together, as will be more fully described later herein.

To enable the evening up of the fabric to be obtained in the manner aforesaid, the knitting butts 20a of the fashioning needles 20 are made higher than the knitting butts 18a of the ordinary needles in the coarse gauge section, and those ordinary needles which are associated with fashioning needles are furnished with butts 19a, 19b, of two heights, one higher and one lower than the knitting butts 18a on the other ordinary needles. The high butts 20a on the fashioning needles ensure an increased action of said needles under the stitch cam 23 (Figure 10) than that imparted to the ordinary needles in the coarse section and consequently said fashioning needles draw the requisite longer loops for evening up the fabric. When the ordinary needles 19 are working alone, i. e. without the associated fashioning needles, the cam 23 engages with the low level butt 19b

70

75

80

85

90

95

100

105

110

115

120

125

130

so that said needles draw short loops, but when the jacks 22 under these needles are raised, following or during the coming into action of the associated fashioning needles, the high level butts 19a are engaged by the cam 23 and consequently long loops are drawn.

The jacks 22 for controlling the knitting action of the ordinary needles 19 are inclined at their upper extremity 22c so that when raised they will press the needle outwards as indicated in Figure 9 and thus bring the high level butt 19a into the plane of the stitch cam 23.

The full complement of ordinary needles is divided into long and short butt groups in the usual manner for making the heel and toe. That is to say, round one half of the needle circle instep needles 18 having long butts 18a are provided, while round the other or heel and toe half, which half, of course, includes the fashioning needles, heel and toe needles 24 having shorter butts 24a are provided, except in the sections 15 and 16 where the needles 19 and 20 are arranged alternately as already described. In the specific example herein described four kinds of needles are provided viz. long butt ordinary needles 18, short butt ordinary needles 24, both these having butts of normal height, fashioning needles 20 with short high level butts 20a and ordinary needles 19 with high and low level butts 19a, 19b.

The jacks 21 and 22 have butts 21a and 22a of uniform length, but those jacks 25 occupying the central position, i. e. those which are to be first operated, have long butts 25a (see also Figure 11). It will be understood that the aforesaid coarse gauge section 14 includes ordinary needles, the majority of which have long butts and the remainder short butts, as illustrated in Figure 5.

For selecting and raising the jacks there is provided a movable cam 26 which is moved by pattern controlled means to raise the long butt jacks 25 to a pre-selected position as shown in Figure 12. For this purpose the cam 26 is mounted on a slide 27 which works in a bracket 28 attached to the machine bed 3, and is engaged by a lever 29 fulcrumed at 30 on the post 31. The lever 29 is connected by a link 32 with a lever 33 pivoted on a pin 34 fixed in the machine frame 4, said lever being acted upon at the time required by a cam 35 on a drum 36 on the pattern shaft 7. When the cam 35 engages the lever 33 the cam 26 is put into action and when the cam 35 releases the lever 33 a spring 37 operates to withdraw the cam 26. Two other cams 38, 39 are provided, the cam 38 being fixed and the cam 39 movable into and out of action by pattern-controlled means. The first of these cams, i. e. the fixed one 38, is a raising cam which raises the pre-selected jacks 25 to full height to bring the adjacent jacks 21 and 22

into action to control the knitting function of the corresponding needles as already described. It should be understood that the two jacks 25 are respectively arranged under the outside needles of the group in section 17

70 which needles are always at the higher level so as to knit at every revolution. Thus the

raising of these jacks 25 has no influence upon their corresponding needles, but is employed solely for commencing the fashioning operation.

Each of the jacks 25 is furnished with a foot 25b which, when the jacks are raised by the cam 38, is adapted to engage the butts 21a and 22a of the jacks 21 and 22 (see Figure 13) to raise the latter for the purpose

80 mentioned. The second cam 39 is a depressing cam and its function is to depress those jacks which have been pre-selected by the raising of the previous jacks. It will be remembered that each pair of jacks 21 and 22,

25 when raised pre-selects the next adjacent pair of jacks, for which purpose each jack 22 is furnished with a foot 22b for engagement with the butts on the next pair of jacks, and if it is not desired that such pre-selected jacks

90 should be raised, then they are depressed by the depressor cam 39. By moving the depressor cam 39 to its inactive position in which it is represented in Figure 15, the pre-selected jacks, on the next revolution, come

95 round in a position to be raised by the raising cam 38, as shown in Figure 16. Thus by moving the depressor cam into and out of action by pattern controlled means the fashioning needles can be brought into action at

100 desired intervals. While the said cam is in action no further selection of the jacks takes place, consequently any desired number of courses can be knitted between the successive fashioning needles coming into action. If the depressor cam is held out of action there is a selection and raising of the jacks at each revolution.

For operating the cam 39 the latter is slidably mounted in a block 40 on the machine bed 3 and has a pin 41 therein engaged by one end of a lever 42 fulcrumed at 43 on the machine bed and having its opposite end connected by a link 44 with a lever 45 on a rock-shaft 46. The rockshaft has thereon another lever 47 connected by a link 48 with a slide 49 mounted adjacent to a ratchet wheel 50 rotatable on a shaft 51 carried by the machine frame 4. The ratchet wheel has a series of holes 52 therein for the reception of one or

110 more pins 53 according to requirements. The slide 49 has a tooth 54 thereon for engagement by the one or more pins in the ratchet wheel whereby the slide is raised momentarily to withdraw the cam 39. The ratchet wheel is

115 rotatable during the fashioning operation by a pawl 55 mounted eccentrically on a shaft 56 rotatable in the machine frame and driven by means of a pinion 57 from the aforesaid gear 11. The pawl 55 is controlled by a

120

125

130

bluff 58 on a slide 59 connected by a link 60 to a lever 61 freely mounted on the rockshaft 46. The lever 61 is connected by a link 62 with another lever 63 pivoted on a bracket 64 on the machine bed, said lever 63 being in turn connected by a link 65 with another lever 66 fulcrumed on the pin 34 and held in engagement with a cam 67 on the drum 36 by a spring 68. This cam by causing the lever 63 to engage the lever 42, holds the cam 39 out of action and also maintains the bluff 58 in contact with the pawl 55 so that the latter reciprocates idly while the machine is knitting ordinarily. At the commencement of the 15 fashioning operation a gap in the cam 67 is brought opposite to the free end of the lever 66 whereupon the latter moves under the action of a spring 68 to allow the cam 39 to go into action and to release the pawl 55, i. e. by 20 moving the bluff 58 so that the pawl commences to operate the ratchet wheel. When during the rotation of said wheel a pin therein engages the tooth 54 on the slide 49 the latter, as aforesaid, is operated momentarily 25 to withdraw the cam 39 so that there is a selection of jacks as previously described. The rate of rotation of the ratchet wheel in relation to the needle cylinder and the number of pins therein determines the number of courses 30 between the successive fashioning needles coming into operation. At the end of the fashioning operation the cam 67 operates the lever 66 to withdraw the cam 39 and render the pawl 55 inoperative.

35 A further cam 69 may be inserted between the cams 38 and 39, which may be termed a positioning or levelling cam, its function being to position the pre-selected jacks 21 and 22 (as represented in Figure 14) to ensure that 40 their butts 21a, 22a engage the depressing cam, when the latter is in action, or to ensure that said butts are brought round in the correct position for engagement by the raising cam 38 when the depressing cam is out of action. A small projection 22d is provided on 45 each of the jacks 22 which engages the butt 21a on its associated fashioning needle jack 21 to bring the latter down when it is itself depressed.

50 The stitch cam 23, clearing cam 70, centre cam 71 and guard cam 72 for the needles are appropriately arranged to permit the operations of the jacks upon said needles taking place. Instead of raising and selecting the 55 fashioning needles one at a time I may selectively raise two or more at a time.

It is to be understood that the fashioning of the tubular fabric is effected during circular knitting by widening as the result of 60 increasing the number of needles in action. Normally the fashioning needles 20 travel along an idle track α as indicated in Figure 10, while the ordinary needles are raised to a higher track γ to knit by a cam 73, the 65 fashioning needles being raised to this higher

track, when required, by the cam 38 as already described. It will be understood that after all of the fashioning needles have been brought into operation, e. g. for shaping the leg of the article, they continue to knit along 70 with the ordinary needles and the stepped butt needles continue to even up their loops with the loops formed by the other needles for the required number of courses, e. g. to form the remainder of the leg of the article. 75 Prior to commencing another article the fashioning needles press off their loops and are returned to the non-knitting track. This return is brought about by an appropriate cam system. The butts 20a of the fashioning 80 needles are shorter than the butts 24a of the short butt ordinary needles 24 and after all the needles have been raised, and when it is required to take out the fashioning needles, a cam 74 is put into action which moves all 85 the raised ordinary needles 18, 19 and 24 down, but misses the short butts of the fashioning needles so that the fashioning needles pass the feeding point in a raised position.

To this end the cam 74 is attached to a slide 90 75 mounted in a block 76 secured on the cam carrier 2. The slide is connected by a lever 77 pivoted on a pin 78 in the block 76 and connected by a link 79 with a lever 80 pivoted on the pin 34 and acted upon by a cam 95 81 on the drum 36 whereby the cam is put into action when required against the action of a spring 82. When the cam 81 moves from under the adjacent end of the lever the spring withdraws the cam 74. Just prior 100 to the fashioning needles reaching the feeding point, the feeder 83 is moved out of action so that said needles take no yarn but press off and pass to the lower or idle track. The feeder is put out of action by the usual means 105 comprising lever 83, link 84, and lever 85 acted upon by a cam 86 on the existing drum 6. On the next revolution the ordinary needles are again raised to knit by the cam 73.

The cam 73 is also movably arranged so 110 that it can be put into a position to engage all the needle butts when the fashioning needles are required to press off and thus ensure that all of the fashioning needles rise above the cam 70, said cam being withdrawn 115 slightly so that it misses the butts of the fashioning needles after the cam 74 has acted thereon. Accordingly the cam 73 is formed on a slide 87 having connected to it a lever 88 pivoted on the pin 78 and connected by a link 89 with a lever 90 pivoted on the pin 34. The lever 90 is acted upon when required by a cam 91 on the drum 36 whereby the cam 73 is moved into the innermost position. The lever 90 is held in contact with the drum 36 by a spring 92. The jacks are taken out of action at the appropriate time by a pattern-controlled movable cam 93.

This cam is formed by a plate slidable in a block 94 on the machine bed 3 and may 130

be connected by a pin 95 with a lever 96 on a spindle 97 rotatable in a bracket 98 on the machine bed. The spindle has another lever 99 thereon connected by a link 100 and lever 101 with a slide 102 in a block 103 on the machine bed, the lever 101 being fulcrumed at 104 on the block. The slide 102 is connected to another slide controlled by a spring 105 and furnished with a block 106 for engagement with a cam 107 on the drum 36 whereby the cam 93 is held withdrawn until a gap 108 comes opposite the end of the lever whereupon the cam 94 is moved into action. A cam 109 may be provided to hold the needles 10 down when the jacks 22 enter the back thereof, as shown in Figure 9, for the purpose already mentioned, said cam being put into action and withdrawn simultaneously with the insertion and withdrawal of the cam 26. For this purpose the cam 109 is formed on a slide 110 connected by a lever 111 pivoted on the pin 78 and a link 112 with the lever 33.

When, as may be the case, fashioning needles are disposed or associated with ordinary needles in a needle cylinder having grooves of uniform circumferential pitch, the fashioning or variation in diameter of the knitted tube may be brought about by bringing the fashioning needles into action in groups, (one or more needles at a time in each group), or the increase may commence at one point and progress in one or each direction around the cylinder. The evening up may be achieved in a manner similar to that already described herein.

Figure 17 shows a cylinder 16 having uniformly spaced needle grooves 1c and Figure 18 illustrates diagrammatically a convenient distribution of the ordinary and fashioning needles around the cylinder. For example there is provided a group 112 of long butt or instep needles 18 and a group 113 of short butt needles comprising ordinary needles 24 at opposite ends of the group 112 and a number of ordinary stepped butt needles 19c and fashioning needles 20b i. e. needles similar to the needles 19 and 20 shown in Figure 6, arranged alternately. In this arrangement the number of ordinary short butt needles in the group 113 is equal to the number of long butt needles in the group 112 so that when the fashioning needles are idle there are as many heel and toe needles in operation as there are instep needles. Owing to the number of fashioning needles employed however, the ordinary short butt needles occupy more than half of the circumference of the needle cylinder.

When the fashioning needles are idle the butts thereof follow the track x while the butts of the ordinary needles follow the track y , Figure 10, as already described herein.

Jacks 21, 22 and 25 (Figure 7) are associated with the fashioning and stepped butt

needles and controlled as and for the purposes previously described herein with reference to Figures 10 to 13. However since the needle grooves are equally spaced the stepped butt needles are adapted to draw shorter loops than the other ordinary needles when the fashioning needles are idle and to draw loops of equal length to those drawn by the other ordinary needles during the fashioning operation, and for the required number of courses thereafter. The fashioning needles are also adapted to draw loops equal in length to those drawn by the other needles when put into action.

The long butt jacks 25 (Figure 7) whereby the fashioning operation is initiated may be arranged side by side centrally in the group of jacks.

Alternatively as represented in Figure 19, there may be two groups 114, 115 of fashioning and stepped butt needles arranged alternately, said groups being separated by a small group 116 of ordinary needles 24, as in the arrangement shown in Figure 5, in which case the jacks 25 would be correspondingly separated, e. g. as shown in Figure 11. Further either the number of ordinary short butt needles 24 or the number of fashioning needles and stepped butt needles would be correspondingly reduced so as to keep the number of ordinary short butt needles the same as the number of ordinary long butt needles 18.

I may, if desirable or necessary, provide suitable means for adjusting the sinkers or equivalent instruments to facilitate evening up the fabric, i. e. obtaining uniformity of loop.

What I claim then is:—

1. A circular knitting machine for the production of fabric fashioned by the introduction of additional loops which includes a needle cylinder, a stitch cam, a series of independent needles in said cylinder comprising ordinary needles interspersed with fashioning needles, the latter being normally inoperative and the ordinary needles adjacent to the fashioning needles being furnished with stepped butts, means for bringing the fashioning needles into action selectively, and means for controlling the ordinary needles adjacent to the fashioning needles so that the stitch cam engages the low portions of the stepped butts prior to the fashioning operation and the higher portions during said operation, for the purpose set forth.

2. A circular knitting machine for the production of fabric fashioned by the introduction of additional loops including a needle cylinder, a series of independent needles comprising ordinary needles interspersed with fashioning needles, the latter being normally inoperative, a series of interengaging jacks associated with the fashioning needles, means for operating jacks corresponding with the

- fashioning needles to put the said needles into action, certain jacks being operable initially to pre-select co-adjacent jacks for operation by said means, which operation causes 5 pre-selection of the next adjacent jacks for the same purpose, and so on throughout the series of jacks, and means whereby the ordinary needles adjacent to the fashioning needles are caused to even up their loops with 10 the loops formed by the other needles both prior to and during the fashioning operation.
3. A circular knitting machine for the production of fabric fashioned by the introduction of additional loops, which includes a 15 needle cylinder, a series of independent needles comprising ordinary needles interspersed with fashioning needles, the latter being normally inoperative, a series of interengaging jacks associated with the fashion- 20 ing needles, a fixed cam for operating jacks corresponding with fashioning needles to put said needles into action, certain jacks being operable initially for actuation by said fixed cam to pre-select co-adjacent jacks for en- 25 gagement with said cam whereby pre-selection of the next adjacent jacks for the same purpose is effected and so on throughout the series of jacks, an automatically controlled cam for effecting said initial operation, and 30 means for causing the ordinary needles adjacent to the fashioning needles to even up their loops with the loops formed by the other needles both prior to and during the fashioning operation.
- 35 4. A circular knitting machine for the production of fabric fashioned by the introduction of additional loops which includes a needle cylinder, a series of independent needles comprising ordinary needles inter- 40 spersed with fashioning needles, the latter being normally inoperative, a series of interengaging jacks associated with the fashioning needles, a fixed cam for operating jacks corresponding with fashioning needles 45 to put said needles into action, certain jacks being operable initially for actuation by said cam to pre-select co-adjacent jacks for opera- 50 tion by the fixed cam whereby pre-selection of the next adjacent fashioning jacks is ef- 55 fected and so on throughout the series, an automatically controlled cam for effecting said initial operation, means for determining the engagement of the pre-selected fashioning jacks with the fashioning cam, and con- 60 sequently the intervals at which the fashioning needles are put into action and means whereby the ordinary needles adjacent to the fashioning needles are caused to even up their loops with the loops formed by the 65 other needles both prior to and during the fashioning operation.
5. A circular knitting machine for the production of fabric fashioned by the introduction of additional loops, which includes a 70 needle cylinder, a stitch cam, a series of inde- 75 pendent needles in said cylinder comprising ordinary needles interspersed with fashioning needles, the latter being normally inoperative and the ordinary needles adjacent to the fashioning needles being furnished with stepped butts, jacks associated with the fashioning needles, means operative upon the jacks for bringing the fashioning needles into operation selectively and means for controlling the ordinary needles adjacent to the fashioning needles so that the stitch cam engages the lower portions of the stepped butts prior to the fashioning operation and the higher portions during said operation for the purpose set forth.
6. A circular knitting machine for the production of fashioned fabric by the introduction of additional loops, which includes a 80 needle cylinder, a stitch cam, a series of independent needles in said cylinder comprising ordinary needles interspersed with fashioning needles, the latter being normally inoperative and the ordinary needles adjacent thereto being furnished with stepped butts, a series of interengaging jacks associated with the fashioning needles, means for operating jacks corresponding with fashioning needles to put said needles into action, certain jacks being operable initially to pre-select co-adjacent jacks for operation by said 85 means, which operation causes pre-selection of the next adjacent jacks for the same purpose, and so on throughout the series, the means for controlling the ordinary needles adjacent to the fashioning needles so that the stitch cam engages the low portions of the stepped butts prior to the fashioning operation and the higher portions during said 90 operation for the purpose set forth.
7. A circular knitting machine for pro- 95 ducing fabric fashioned by the introduction of additional loops which includes a needle cylinder, a stitch cam, a series of independent needles in said cylinder comprising ordinary needles interspersed with fashioning needles, the latter being normally inoperative, and the adjacent ordinary needles being furnished with stepped butts, a series of interengaging jacks associated with the fashion- 100 ing needles a fixed cam for operating the fashioning jacks to put the fashioning needles into action, certain jacks being operable initially for actuation by said fixed cam to pre-select co-adjacent fashioning jacks for opera- 105 tion by the fixed cam whereby pre-selection of the next adjacent jacks for the same purpose is effected, and so on throughout the series, an automatically controlled cam for effecting said initial operation and means for controlling the ordinary needles adjacent to the fashioning needles so that the stitch cam engages the low portions of the stepped butts prior to the fashioning operation and the higher portions during the said operation, for the purpose set forth.

8. A circular knitting machine for producing fabric fashioned by the introduction of additional loops, which includes a needle cylinder, a stitch cam, a series of independent needles in said cylinder comprising ordinary needles interspersed with fashioning needles, the latter being normally inoperative, and the adjacent fashioning needles being furnished with stepped butts, a series of inter-
5 engaging jacks associated with the fashioning needles, a fixed cam for operating the fashioning jacks to put the fashioning needles into action, certain jacks being operable initially for actuation by said fixed cam to
10 pre-select co-adjacent jacks for operation by the fixed cam whereby pre-selection of the next adjacent jacks for the same purpose is effected, and so on throughout the series, an automatically controlled cam for effecting
15 said initial operation, means for determining the engagement of the pre-selected fashioning jacks with the fixed cam and consequently the intervals at which the fashioning needles are put into action, and means for control-

both prior to and during the fashioning operation, and for the required number of courses thereafter.

15. A circular knitting machine for producing fabric fashioned by the introduction of additional loops, including a needle cylinder, a series of independent needles in said cylinder comprising ordinary needles with ordinary butts, fashioning needles having short butts and normally idle and ordinary needles having stepped butts and adapted to draw shorter loops than the other ordinary needles prior to the fashioning needles coming into action and to draw loops of equal length to those drawn by the other needles when the fashioning needles come into action, means for bringing the fashioning needles into action selectively and means for controlling the stepped butt needles.

- 20 16. A circular knitting machine for producing fabric fashioned by the introduction of additional loops, including a needle cylinder, a series of independent needles in said cylinder comprising ordinary needles having ordinary butts, fashioning needles normally idle and having short high level butts whereby, when in action, said needles are caused to draw loops longer than those drawn by the said ordinary needles, ordinary needles having stepped butts and adapted to draw loops shorter than those drawn by the other ordinary needles prior to the fashioning operation and to draw loops longer than those drawn by the remaining ordinary needles 35 when the fashioning needles come into action, said fashioning needles and stepped butt needles being located in a section of the needle cylinder which is of finer gauge than that of the section in which the remaining 40 needles are located, means for bringing the fashioning needles into action selectively and means for controlling the operation of the stepped butt needles.

- 45 17. A circular knitting machine for producing fabric fashioned by the introduction of additional loops, including a needle cylinder, a series of independent needles comprising ordinary needles, fashioning needles normally idle and ordinary needles having 50 stepped butts, jacks associated with the fashioning needles, means operative upon the jacks for bringing the fashioning needles into operation selectively, jacks associated with the stepped butt needles and operable 55 in conjunction with the other jacks to control said needles so as to cause same to even up their loops with the loops formed by the other operative needles both prior to and during the fashioning operation and for the 60 required number of courses thereafter, means for causing the fashioning needles to press off and means for rendering the said fashioning needle jacks inoperative subsequent to the fashioning operation.

- 65 18. A circular seamless hosiery knitting

machine for producing hose fashioned by the introduction of additional loops, including a needle cylinder, a series of independent needles comprising a group of instep needles, a group of heel and toe needles interspersed with fashioning needles normally idle and including ordinary needles with stepped butts, means for bringing the fashioning needles into action selectively and means for causing the stepped butt needles to even up their loops with the loops formed by the other operative needles both prior to and during the fashioning operation and for the required number of courses thereafter.

In testimony whereof I have signed my name to this specification.

PER CHRISTIAN CHRISTENSEN.
